**COMBINED PARKING LAMP LENS AND FRAME
THEREFOR**

Richard A. Teague, Rochester, Mich., assignor to Stude-
baker-Packard Corporation, a corporation of Michigan

Application November 1, 1954, Serial No. 32,906

Term of patent 14 years

(Cl. D48—32)

FIG. 1

FIG. 3

FIG. 4

FIG. 2

Figure 1 is a perspective view in reduced scale of a combined parking lamp lens and frame therefor, in accordance with my new design.

Figure 2 is a view in section taken along the lines 2—2 of Figure 1;

Figure 3 is a front elevational view; and

Figure 4 is a side elevational view thereof.

The automobile disclosed by means of broken lines in Figure 1 is shown only for the purpose of illustration.

I claim:

The ornamental design for a combined parking lamp lens and frame therefor, as shown and described.
